APPARATUS FOR FEEDING, SEVERING,
STRIPPING, AND BENDING HOOKED
WIRE LEADS

John Vollmer, Springdale, Conn.

Application August 6, 1948, Serial No. 42,835

19 Claims. (Cl. 140—1)

1

This invention relates to a device for bending an end of a wire lead for electrical devices, and more particularly to a device operating with and as a part of a machine which automatically cuts these leads to length and strips a certain amount of insulation from the opposite ends of the cut lengths in preparation for making the electrical connections of these leads in electrical devices, such, for example, as electrical dry shavers and other electrical devices.

It has for an object to provide a device which will operate automatically with the lead cutting and stripping device to bend one end of the stripped wire or lead to form a hook, or a complete loop or eye, to facilitate making the electrical connection of the leads in these electrical devices, and to do this bending automatically in conjunction with and operated by and as a part of the cutting-off and stripping machine, so that as the leads leave this machine they are complete and ready for assembling and connecting them in the electrical device.

A further object is to provide a device of this character which may be assembled and applied to lead wire cutting and stripping machines already installed, and which will use motions and operations of this machine as a part of the operation of bending one end of the stripped lead.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

In these drawings:

Fig. 1 is a front elevation of the machine with parts broken away to more clearly show the construction;

Fig. 2 is a sectional view along line 2—2 of Fig. 1 showing a top plan view of a cam for controlling the opening and closing of the wire feed fingers and connected parts;

Fig. 3 is a partial section and partial side elevation showing the wire feed fingers;

Fig. 3a shows these fingers in dotted lines in closed position;

Fig. 4 is a front elevation of the feed mechanism on a larger scale than Fig. 1 showing it in another position from that of Fig. 1, various associated parts being shown in section, this section being substantially on line 4—4 of Fig. 5;

Fig. 5 is a top plan view of the lead wire cutting-off and stripping mechanism;

2

Fig. 5a is a face view of a pair of the stripping knives in the closed position;

Fig. 5b is a similar view showing the knives in the open or separated position;

Fig. 6 is a rear elevation of the main portions of the machine with the rear wall of the base frame or housing broken away to show the various cams and associated elements;

Fig. 7 is an elevational view looking from the right of Fig. 6 showing part of an operating shaft;

Fig. 8 is a top plan view of the feed cam;

Fig. 9 is a top plan view of the stripping cam and associated parts, a portion of the housing being shown in section;

Fig. 10 is a detail elevation of the mounting connection of certain of the parts looking from the right of Fig. 9;

Fig. 11 is a top plan view of the bending device showing how it is applied to the machine frame;

Fig. 12 is a top plan view of a form of bending device for bending a hook in the end of the lead wire, showing the jaws open, but after some movement from the full open position;

Fig. 13 is a view of the front ends of the jaws showing them in the next position;

Fig. 14 is a similar view showing the jaws in the closed position;

Fig. 15 shows the jaws again open at the end of the cycle, just before removal of the bent lead wire;

Fig. 16 is a side elevation looking from the right of Fig. 12;

Fig. 17 is an end elevation looking toward the bottom of Fig. 12;

Fig. 18 is a top plan view with the jaws removed;

Fig. 19 is a longitudinal section substantially on line 19—19 of Fig. 12;

Fig. 20 is a transverse section substantially on line 20—20 of Fig. 12;

Fig. 21 is a transverse section substantially on line 21—21 of Fig. 13;

Fig. 22 is a plan view of a bent end of the lead wire showing the open or hooked end;

Fig. 23 is a similar view showing the closed or eyelet loop;

Fig. 24 is a view similar to Fig. 12 showing a plan view of a modified arrangement of jaws for bending a complete loop or eyelet in the stripped end of the lead wire and showing the jaws in the open position. It also shows the stripped end of the lead wire in position for the bending operation;

Fig. 25 is a longitudinal section substantially on line 25—25 of Fig. 24;

Fig. 26 is a top plan view of the jaws of Fig. 24 showing the next position;

Fig. 27 shows these jaws in the next position, and

Fig. 28 shows the jaws in the next position with a looped lead wire.

The machine comprises a base 1 on which is mounted the machine frame or housing 2. At the lower part of this frame is the main drive shaft 3 (Figs. 1 and 6) operated by any suitable means such, for example, as electric motor 4, and at the opposite end may be a hand wheel 5 to permit hand operation of the machine for setting up and adjusting purposes. On the shaft 3 is a worm 6 meshing with the worm wheel 7 secured on the upright cam shaft 8 for driving it, and secured on this shaft are the various operating cams comprising the feed cam 9, the cam 10 for shifting the wire gripping means for performing the stripping operations, the cam 11 for operating the cutting-off and stripping slides, and the cam 12 for controlling the opening and closing of the gripping fingers for the stripping and feeding operations. Cams 10 and 11 are combined on one member 13, cam 10 being cut in the top of this member and the cam 11 in the under side thereof. Also mounted in the frame but located to one side of the shaft 8 is an upright intermediate or pilot shaft 14 forming supports and pivots for certain of the arms and levers operated by certain of these cams.

The feed operating cam 9 (Figs. 6 and 8) includes a cam groove 15 in which runs the roller 16 on a lever arm 17 pivoted at 18 to a bracket 19 on the machine frame, and adjustably mounted on this lever arm is a block 20 to which is pivotally connected a link 21 pivotally connected at 21a to a feed arm 22 (Fig. 9) pivoted at 23 on an offset lever 24, pivoted at 25 to the bracket arm 26 mounted on the machine frame. The outer end of this offset lever is pivotally connected at 27 to a link 28 pivoted at 29 to an arm 30 of the bell crank lever 31 pivoted to turn freely on the pilot shaft 14, the other arm 32 carrying the roller 33 running in the cam slot 34 of the cam 10. On the front upper part of the machine is a horizontal guide 35 on which is mounted the head 36 (Figs. 1 and 4) for longitudinal sliding movement, this head being adjustably connected at 38 through the rod or link 37 to the other end of the feed arm 22 for sliding this head 36 in certain timed relation by the action of cams 9 and 10 (Figs. 6, 8 and 9) as will be more fully described later. The arm 22 comprises two members 22a (Fig. 10) arranged in a sort of V, and the offset lever 24 is located between and pivoted to the rear ends of these members.

Carried by this head 36 are the feed jaws 39 (Figs. 1, 3 and 4) for gripping and feeding the insulated wire 40. There are a pair of these jaws opposed to each other pivoted on shafts 41 and connected by segmental gears 42 so that the jaws will work together, the jaws each comprising a series of fingers 43 and they are operated by a link construction including an arm 44 (Figs. 1, 3a and 4) connected by a link 45 to another arm 46 slidable on a square shaft 47 with the head 36, this shaft being mounted to turn in suitable bearings 48 on the frame 2. This square shaft 47 is operated by a lever arm 49 (Figs. 2, 3 and 6) connected by link 50 to an arm 51 secured on an upright shaft 52 mounted in suitable bearings 53. Secured to the lower end of shaft 52 is another lever 54 connected by the link 55 to the arm 56 pivoted and free to turn on the shaft 14. This

arm carries a roller 57 running in a cam slot 58 in the finger control cam 12 (Figs. 1, 2 and 6).

Mounted on the front of the machine frame is the lead wire cutting and stripping device 59 (Figs. 1, 4 and 5). This comprises a bracket or base 60 in which is mounted a pair of slides 61 and 62 movable horizontally toward and from each other and carrying the lead wire cutting-off knives 65 and 66, and stripping knives 63 and 64, and 67 and 68, these knives being arranged in pairs opposed to each other as shown in Fig. 5, and with the knives 63, 65 and 67 carried by the slide 62, and the knives 64, 66 and 68 carried by the slide 61. These knives have opposed V-shaped knife edge cutting ends, as shown in Figs. 5a and 5b, the edges 61a and 68a of knives 67 and 68 only being shown in these figures. Slide 62 is operated by an arm 69 pivoted to turn on the shaft 14 and carrying a roller 70 running in a cam groove 71 in cam 11. The slide 62 is connected to slide 61 by a bar 72 having a rack 73 meshing with an intermediate pinion 74 meshing on its opposite side with a rack 75 on the slide 61, the pinion being on a shaft 76 mounted in the bracket 60. It will be understood with this arrangement the slides 61 and 62 are connected together to move simultaneously in opposite directions, so that when the slide 62 is moved inwardly toward the wire 40 by the cam operated arm 69, the slide 61 will be simultaneously shifted toward the wire from the opposite side. Similarly, when operated in the opposite direction they will move away from the wire simultaneously.

The bending device is indicated as a whole by the numeral 77 (Figs. 1, 4, and 11 to 21) and is mounted by a bracket 78 through an arm 79 on the frame 2 of the machine by any suitable means, such as the screws or bolts 80 (Fig. 11). The bracket includes a forward horizontal guide arm 81 having on its front wall a T-rib 82 forming a slide and guide support for the base block 83 of the bending device, the inner edge of the block 83 being provided with a similarly shaped slot 84 running on the T-rib or guide. On the top of this block 83 are laterally spaced overhanging side flanges 85 and 86 (Figs. 17, 18 and 20) forming guides for the opposite edges of a sliding plate 87, provided at one end with an upstanding block or lug 88. This could be integral with the plate, or as in the structure shown, could be a separate member secured to the plate by any suitable means, such as the screws 89. Pivotable on the top of the slide plate 87 is a pair of levers 90 and 91 carrying at their forward ends bending jaws 92 and 93 opposed to each other, the pivots being shown at 94.

The base 83 is provided with a pair of laterally spaced longitudinal slots 95 (Figs. 12, 18 and 21), the main portions of which are substantially parallel and each having at its forward end an inclined portion 96, these portions inclining outwardly in opposite directions, as shown in Figs. 12 and 18. In these slots are operating pins or rollers 97 for the levers 90 and 91 and the jaws 92 carried thereby, and the under side of the base 83 is provided with elongated recesses 98 following the slots 95 and 96 to receive the heads 99 of these pins. These pins pass through openings 87b (Fig. 21) in the slide 87 large enough to permit the necessary lateral movement of the pins and are seated in openings 100 in the levers 90 and 91. The jaw 92 is a horizontally projecting rounded rib formed as part of block 101 which is secured to the lever 90 by any suitable means, such as the block or plate 102 fastened by the

screws 103. The jaw 93 is formed as part of a similar block 104 held in a recess in the lever 91 by plate 105 secured by the screws 106. Jaw 93 comprises a horizontally projecting rib rounded on the rear or inner side toward the jaw 92, and the jaw 93 as shown in Figs. 12 and 15 is arranged with the offset side forwardly of the end of the jaw or rib 92 a distance equal to about the thickness of the stripped wire 40b.

Mounted for sliding movement in the lever 91 is a slide 107, this slide being mounted by means of a T-shaped rib 108 (Figs. 20 and 21) running in a similarly shaped groove in the side of the lever. It is normally held in the retracted position of Fig. 12 by means of a spring 109 seated at its opposite ends in recesses in the slide 107 and the block 104 of the jaw 93. This slide has an offset end or extension 110 in the form of a straight lug for a purpose presently to be described. The base 83 is provided with a longitudinal slot 111 in its top wall in which is mounted a key 112 extending through slot 87a in plate 87 for operating the slide 107, this key having a lug 113 on its upper edge seating in a notch in the under side of slide 107. Stop pins 114 and 115 suitably spaced in this slot form limit stops for movement of the key 112 and the slide 107, and stop 115 acts as a means to retract slide 107 in case of failure of spring 109.

Movement of the block 83 on the guide 82 is determined by an adjustable stop formed by the end 116a of a bar 116 mounted on the front of the guide 82 and adjustable longitudinally thereon by a clamping screw 117 in an elongated slot 118 in the stop. A spring 119 (Fig. 1) connected to the lug or block 88 by having its ends passing through an opening 120 in the block and secured at its other end to the bracket 60 tends to shift this whole device to the left as viewed in Fig. 1, or downwardly as viewed in Fig. 12 for the reverse or return movements. The jaw block 101 is provided with a recess 121 in which is a release or stripper member 122 at the inner side of the jaw 92. It is mounted on a rod 123 slideable in the block 102 and is embraced by a spring 124 which tends to move it outwardly or downwardly as viewed in Fig. 12, and mounted on the base 83 is a stop 125 adapted to be engaged by the end of the rod 123 at the end of the outward or reverse movement of the slide plate 87 to push this rod and the stripper 122 inwardly to release the bent wire from the jaw 92 at the end of the cycle, as will presently be described.

The operation is as follows:

We will assume that the insulated wire 40 (Figs. 1, 4 and 5) has been drawn from the supply spool or reel 126 and a lead of proper length has been cut off and bent and discharged from the machine. The end of the wire is then against the cut-off knives 65 and 66 of Fig. 5. The finger grips 43 are to the left of these knives, as indicated in dotted lines 43a (Fig. 4) and it will be seen that in this position, as shown in Fig. 5, the forward end portion 40c of the insulation is between the cut-off knives 65 and 66 and the stripper knives 63, 64. The stripper knives 63, 64 and 67, 68 are set so as to move just far enough to cut through the insulation but not to cut the metal wire, as shown in Fig. 5a. The cam 12 by operating the square shaft 47 clamps these fingers 43 onto the wire so as to grip it. Now the cam 10 shifts the offset lever 24 (Fig. 9) through the bell crank 32 inwardly as viewed in Fig. 9, which thus throws the pivot 23 of the feed arm 22 outwardly or to the right as viewed in

Fig. 9. This swings this arm 22 about the connection 21a which is a pivotal connection to the link 21 which is now stationary, and thus swings the free end of the lever arm 22 to the left as viewed in Fig. 9. This action, through the rod 37, shifts the head 36 and the fingers 43 a short distance to the left from the dotted position 43a to the dotted line position 43b Fig. 4. This movement carries the wire 40 with the fingers 43 stripping the length 40c of the insulation from the end of the wire, which is the short end of this wire.

At this time feed cam 9 operates the feed arm 22 to the right, as viewed in Figs. 1 and 4, and the cam 11 through the arm 69 shifts the blocks 61 and 62 outwardly to separate the cutter and stripper blades, which permits the fingers 43 gripping the wire 40 to pass to the right between these blades to the full line position 43c of Fig. 4. This action of the gripping fingers, of course, carries with them the wire with the stripped end 40b, and now the cam 11 shifts the blocks 61, 62 in the opposite direction to close the stripping and cut-off blades to the position of Fig. 5. In this action the cut-off blades 65, 66 cut off the length of lead wire 40a, the blades 63 and 64 cut the insulation to the left of these blades, as above described, while the blades 67 and 68 cut the insulation at the proper distance to be stripped from the rear end of the cut off length 40a, this length being shown at 40d. After this action the cam 10 shifts the offset lever 24 (Fig. 9) to the left about its pivot 25 or toward the front of the machine, swinging the pivot 23 to the left as viewed in Fig. 9, thereby swinging the free end of the arm 22 to the right (link 21 and pivot 21a being stationary) and through the rod 37 shifts the head 36 and the fingers 43 to the right to the dotted line position 43d in Fig. 4. This will strip the insulation 40d (Fig. 5) from the rear end of the cut-off lead 40a.

At the beginning of this stripping action the forward stripping end 40b is in position to be formed between the jaws 92, 93 (Fig. 12). As the head 36 carrying the gripping fingers 43 moves forwardly for this stripping action, a stop lug or arm 127 (Figs. 1, 4, 12, 16 and 19) hits the head or lug 88 of the bending device, as shown in Fig. 4, and therefore carries this lug and the slide plate 87 and the bending jaws carried by this plate along with it to the dotted line position 88a. This is also the position of Figs. 14 and 19. Movement of the base 83 is prevented by the adjustable stop member 116, and this stop member can be adjusted to position the base 83 and therefore the bending device at the proper position to start this movement of plate 87 at the proper time with the head 36. As previously stated, when this movement of the plate 87 starts, the stripped end 40b of the insulated cut-off lead 40a is inserted between the bending jaws 92 and 93, and as the plate 87 together with these jaws now moves forwardly at the same speed as the head 36 and the fingers 43 carrying this cut-off strip 40a, it remains in this relative position with respect to these jaws. During the first part of this forward movement, the rollers or pins 97 move along the inclined portions 96 of the slots 95 and by swinging the levers 90 and 91, move the jaws 92 and 93 inwardly toward each other against the opposite sides of the stripped wire 40b to the position of Fig. 13. It will be seen that in this position the jaw 93 has bent the free end of the wire around the edge of the jaw 92 through an angle of about 90°, and the insulation on the lead

40a has been gripped by the inner side surfaces 92a and 93a (see Fig. 12) of the jaws so as to hold the wire in proper position in the jaws.

It will be seen from Fig. 13 that in this position the free end of the stripped portion 40b is in alignment with the offset lug or extension 110 on the slide 107. At this point the key 112 (Fig. 19) engages the stop 114, which therefore prevents further movement of the slide 107 forwardly with the plate 87 and the bending jaws. As the plate 87 and the jaws continue to move forwardly, the motion of key 112 and the slide 107 is therefore stopped and continued movement of the jaws with the wire carries them to the position of Fig. 14. As it moves to this position the free end of the wire hits the end of the extension 110 and it is bent to the hooked position of Fig. 14. This completes the bending of the hook in the stripped end of the wire and is the position of Figs. 14 and 19. This movement also, as previously indicated, completes the stripping of the portion of insulation 40d from the rear or left hand end of the cut-off lead 40a.

Cam 12 now opens the feed jaws 39 and feed cam 9 operates to swing the free end of the feed arm 22 to the left or in the return direction and the spring 119 (Fig. 1) moves the slide 87 and the bending jaws backwardly or to the left, until at the end of this movement the end of the stripper rod 123 hits the stop 125 pushing the stripper 122 forwardly, as shown in Fig. 15, to release the bent end of the wire from the jaw 92. In moving to this position the pins or rollers 97 have moved back into the inclined slots 96 and have opened the jaws for the next operation. This releases the bent cut-off lead from the jaws, and as at this time the cam 12 has operated the square rod 47 to open the clamping fingers 43, as shown in dotted lines at 43e (Fig. 3), the cut and stripped lead with the bent end drops from the machine. Continued movement to the left of the head 36 under action of the feed cam 9 and the feed arm 22, and with these fingers 43 in the open position, carries them between the cut-off and stripping knives 63 to 68 to the dotted line position 43a of Fig. 4, in preparation for the next feeding and stripping operation, after which the cycle is repeated. The fingers are closed onto the wire 40, it is shifted to the left to strip the forward end 40c, and then it is fed forwardly for the cutting-off, stripping and bending actions, as described.

Briefly then, the operation is: the fingers grip the wire, shift it a short distance to the left to strip the forward or short end, then these gripping fingers are advanced through the open knives to feed the wire the proper length required. Then the knives close to cut off this length and at this time the forward end which has already been stripped has been inserted between the bending jaws, but movement of the bending device at this point has not started. Then further movement of the head 36 with the gripping fingers advances the cut off wire for the stripping of the rear end of this cut off lead and at the same time moves the jaws of the bending device forwardly with the head 36 and the cut off wire, which movement operates the jaws to bend the forward stripped end of the wire to form the hooked end 40f, as shown in Fig. 22. Then the head 36 and associated parts are shifted to the left or in the reverse direction, permitting the bending jaws to be shifted to the normal and open position by the spring 119, releasing the bent and cut off lead and moving the parts to positions for starting the cycle

all over again. Feed jaws 39 are opened at the beginning of the left hand or reverse motion and the hooked lead is ejected when the jaws of the bending device are opened.

In the form of the device of Figs. 12 to 21, the end of the wire is bent to a hook shape, as shown in Fig. 22. However, it may be desirable to bend it to a complete loop or eyelet, as indicated at 40g (Fig. 23). A bending device modified to secure this result is shown in Figs. 24 to 28. In this device the base 128 corresponds to the base 83 of the devices of Figs. 12 to 21, and has similar overhanging side flanges 129 forming guides for the opposite edges of the movable sliding plate 130 corresponding to plate 87 of the first form. Secured to the forward end of this plate is the same upstanding operating lug or head 88 for shifting this plate and the jaws during the bending operation. Pivoted on the plate 130 by the pivots 131 are the levers 132 and 133 carrying at their free ends the bending jaws 134 and 135, these jaws both being concave jaws, as shown in Fig. 24, and substantially semi-circular in shape, although the jaw 135 is provided with a recess 136 extending inwardly from the end to about half the concave portion on the level with and to receive the lead wire 40a being bent. Between the two jaws 134 and 135 is a slideable pin 137 about which the stripped end of the wire is bent to form the loop or eyelet. This is slideable vertically in an opening in the plate or slide 130, and when the jaws are open it is in the lower or retracted position below the jaws 134 and 135, as shown in full lines in Fig. 25, it being shifted to and normally held in this position by a spring 138. It is shifted to its upper or dotted line position with its upper end between the jaws 134 and 135 during the bending operation by sliding its head 137a on the inclined cam surface 139 formed in the base 128. This base is also provided with two longitudinal slots for operating the bending jaws. The roller or pin 140 in the lever 132 projects into a slot in the base 128 comprising a straight longitudinal portion 141 and at its forward end an inwardly inclined portion 142. A roller or pin 143 in the lever 133 runs in a slot in the base 128 comprising a longitudinal straight portion 144 and a rearwardly and outwardly inclined forward end portion 145. Also mounted in the lever 133 is a slide 146 having a T-rib 147 running in a similarly shaped guide 148 on the inner edge of the lever 133. This slide may move longitudinally of lever 133 and is notched at its rearward end portion as indicated at 149 to provide a reduced offset end or extension 150 similar to the extension 110 of the first form, except that it is considerably longer and is provided with a rectangular opening 151. This slide 146 is operated by a key 152 running in a longitudinal groove 153 in the base block 128 and it operates between two stop pins 154 and 155 projecting into this groove. A lug 156 on the upper edge of this key seats in a similar recess in the under side of the slide 46 for operating it.

In operation, this device goes through the same cycle and series of operations with the feeding head 36 of the machine as the device of Figs. 12 to 21; that is, on the forward movement of the head 36 and the fingers 43 to feed the length of lead 40a to be cut off, the stripped forward end 40b is inserted between the jaws 134 and 135, as shown in Fig. 24. At this point, which is the beginning of the stripping operation for the rear end 40d of the cut off lead length, the lug 127 on

head 36 engages the head or block 88, and during this stripping movement of the cut off lead 40a it shifts the slide 130 to carry it along with this head 36, the same as described in connection with the device of Figs. 12 to 20. During the first part of this movement the cam 139 shifts pin 137 upwardly to the dotted line position of Fig. 25 and to its position between the jaws 134 and 135. During the first part of this movement, as the roller or pin 140 of lever 132 is in the straight portion 141 of the slot in the base block 128, the jaw 134 does not move inwardly, but as roller or pin 143 of lever 133 is in the inclined portion of its operating slot, the jaw 135 is shifted inwardly to the position of Fig. 26. During this movement the slide 146 retains its same position with respect to the lever 133 and the parts are now in the position of Fig. 26. During this movement the jaw 135 has bent the free end 40b of the wire through a right angle about the pin 137 with its free end in alignment with the end of the extension 150. At this point the forward end of the key 152 engages the stop 154 so that further movement of the slide 146 with the slide plate 130 is arrested. Therefore, as the plate 130 and the swinging jaws 134 and 135 carried by it continue to move forwardly, the slide 146 remains stationary and the pin 137 and jaw 135 are carried beyond the free end 150 of the slide to the position of Fig. 27. The jaw 135 and pin 137 are now opposite the opening 151 through the extension 150. In this movement the extension 150 has bent the free end of the wire another 90° about the pin 137, as indicated in Fig. 27. During this movement the roller or pin 143 is moving in the straight longitudinal slot 144 to maintain the jaw 135 stationary and hold the wire on the pin 137. Continued movement of the slide plate 130 forwardly now carries the roller or pin 140 of the lever 132 into the inclined portion 142 of its operating slot, and by camming action of this slot the free end of the lever is swung inwardly carrying the concave jaw 134 to the position of Fig. 28. During this movement the projecting concave jaw 134 is carried through the opening 151 in the extension 150 and completes the bending of the free end of the wire about the pin 137 to complete the closed loop or eyelet shown at 40g in Fig. 23. On reverse movement, or movement to the left, of the feed head 36, this operation is reversed, the slide plate 130 with the parts carried thereby being shifted back to its normal position of Fig. 24 by the spring 119, the same as in the first form. During this movement, the rear end of the key 152 engages the stop 155 and shifts the slide 146 back to its position of Fig. 24. Also, at the end of this reverse movement the head of the pin 137 slides down the cam surface 139, permitting spring 138 to retract this pin out of the loop in the wire, thus releasing this wire and the cut off lead so that it drops from the machine and the device is ready to receive the stripped end of the next cut off lead, and the cycle is repeated. Other means could be used to operate this pin.

Thus it will be seen from the above that the movements and operations of the wire cut off and stripping machine are employed to operate this bending device, this device really becoming a part of the cut off and stripping machine and operates as an integral part of it, and in definite timed and synchronized movement with the movements and operations of this machine, so that now the machine automatically performs the complete operations of cutting off the lead

wire to length, stripping the insulation from predetermined portions of the opposite ends of the cut off length, and then bending the stripped lead at one end to a loop, either an open hooked loop or a closed loop or eyelet. The bending device, however, may be assembled as a distinct unit and applied to cut-off and stripping machines already installed, employing parts and motions of these machines for its operation.

The means described for operating the slides, levers and jaws of the bending device are one effective way of operating them, but it will be understood other operating means may be employed.

An additional advantage to the automatic operation of this device is that the ends of all of the leads are bent uniformly, greatly facilitating the assembly of the leads in the electrical devices. This is not true where the ends are bent by hand, as with hand operation there is considerable variation in the bent ends. Throughout the specification and claims where the term "loop" is employed it is intended to include either the open or hooked form of the loop or the closed loop, unless otherwise particularly stated.

Having thus set forth the nature of my invention, I claim:

1. In a machine for preparing electrical conductor leads comprising means for stripping the insulation from the free end portion of an insulated lead wire, means for feeding the wire forward a given amount to determine the length of the lead, means for cutting off the advanced lead to length, and means for advancing the cut off lead longitudinally, bending jaws arranged to receive the stripped forward end of the wire as it is shifted to the cut off position by the feeding means, and means for operating the jaws during advancing movement of the cut off lead to bend a loop in the stripped end of the wire.

2. In a machine for preparing electrical conductor leads comprising means for stripping the insulation from the free end portion of an insulated lead wire, means for feeding the wire forward a given amount to determine the length of the lead, means for cutting off the advanced lead to length, and forwardly movable means for advancing the cut off lead longitudinally, bending means arranged to receive the stripped forward end of the wire as it is fed forwardly and capable of bending a loop in said wire end, and means operated by forward movement of the lead advancing means for operating the bending means.

3. In a machine for preparing electrical conductor leads comprising means for stripping the insulation from a free end portion of an insulated lead wire, and forwardly movable means for advancing the stripped wire longitudinally, bending means arranged to receive the stripped end of the wire as it is advanced by said means and capable of bending a loop in said wire end, and means operated by further forward movement of the wire advancing means for operating the bending means.

4. In a machine for preparing electrical conductor leads, means for stripping the insulation from a free end portion of an insulated wire including a movable member, means for bending a loop in the stripped end of the wire including a base member, a slide slidable on the base member, a pair of laterally movable jaws on said slide capable of cooperating to bend the end of the wire, cooperating means on the base and slide to operate the jaws by movement of the slide, and

means operated by the movable member to shift the slide to operate the jaws to bend the wire.

5. In a machine for preparing electrical conductor leads, means for stripping the insulation from a free end portion of an insulated wire including a movable member, means for bending a loop in the stripped end of the wire including a base member, a movable slide mounted on the base member, bending means mounted on the slide, means operated by movement of the slide to operate the bending means, and means operable by the movable member to shift the slide to operate the bending means.

6. In a machine for preparing electrical conductor leads, means for stripping the insulation from a free end portion of an insulated wire including a movable member, means for bending a loop in the stripped end of the wire including a base member provided with cam means, a movable slide on said base, opposed jaws on the slide arranged to grip opposite sides of the wire to form the loop, means on the slide cooperating with the cam means to shift at least one jaw to grip the wire by movement of the slide, and means operable by said movable member to shift the slide.

7. In a machine for preparing electrical conductor leads, a base member, a movable slide mounted on said member, means on the slide for bending the stripped end portion of an insulated wire to form a loop comprising a pair of pivoted levers mounted on the slide, opposed bending jaws carried by said levers, said base being provided with cam slots, means carried by the slide running in the slots and connected with the levers for operation by movement of the slide to operate the levers to bend the wire through substantially a right angle about one jaw, a second slide mounted on one lever and provided with an extension at one end movable against said bent end to bend it further about the jaw, a lost motion connection between the second slide and the base including a stop to limit movement of the second slide relative to the base, and means for shifting the first slide to operate the jaws and the second slide.

8. In a machine for preparing electrical conductor leads, a base member, a movable slide mounted on said member, means on the slide for bending the stripped end portion of an insulated wire to form a loop comprising a pair of opposed jaws pivoted to the slide to move toward and from each other, said base being provided with cam slots, means in the slots and connected with the jaws for operating them by movement of the slide to bend a wire about one jaw, a stripping member mounted on a rod slidable in the latter jaw and located in alignment with the bent loop, means for shifting the slide in one direction to close the jaws to bend the loop and to shift the slide in the reverse direction to open the jaws, and stop means to engage the rod at the end of the reverse movement to shift the stripping member to release the bent loop from the jaw.

9. In a machine for preparing electrical conductor leads, a base member, a movable slide mounted on said member, means on the slide for bending the stripped end portion of an insulated wire to form a loop including opposed laterally movable jaws, a slidable pin located between the jaws, cam means in the base, an operative connecting means from the cam means to shift one of the jaws to bend the wire to approximately a right angle around said pin, a second slide hav-

ing lost motion connection with the base and provided with an extension movable between the jaws to engage said bent end of the wire and bend it through approximately a further right angle about the pin, said extension being provided with an opening through it in alignment with the pin after the second bending operation, the other jaw being a concave jaw movable through said opening to bend the free end of the bent wire further about the pin, a second cam means in the base, an operative connection from the latter cam means to the second jaw, means for shifting the first slide to operate the jaws and second slide, and means for withdrawing the pin from the loop at the end of the bending operation.

10. In a machine for preparing electrical conductor leads, means for stripping the insulation from the free forward end portion of an insulated lead wire, forwardly movable means for feeding the insulated wire forward a given amount to determine the length of the lead, means for cutting off the lead at a distance from said stripped end, means forwardly of the feeding means for bending a loop in the stripped end of the wire arranged to receive said end on a forward movement of the wire by the feeding means, and means operated by further forward movement of the feeding means for operating the bending means.

11. In a machine for preparing electrical conductor leads, means for stripping the insulation from the free end portion of an insulated wire lead, forwardly movable means for feeding the insulated lead wire forward a given amount to determine the length of the lead, means for cutting off the lead to length, movable jaws capable of bending the stripped end of the wire between them to form a loop, means for operating the feeding means forwardly to insert the stripped end of the lead in said jaws, and means operated by further forward movement of the feeding means to operate the jaws to form the loop.

12. In a machine for preparing electrical conductor leads, means operable by longitudinal movement of an insulated lead wire for stripping a portion of the insulation from the free end of the wire, forwardly movable means for feeding the insulated lead wire forward a given amount to determine the length of the lead, means for cutting off the lead to length, means for bending the stripped end portion of the lead into a loop, means for operating the feeding means to carry the stripped end to the bending means, and means operated by further movement of the feeding means for operating the bending means.

13. In a machine for preparing electrical conductor leads comprising means for stripping the insulation from the free end portion of an insulated lead wire, forwardly movable means for feeding the wire forward a given amount to determine the length of the lead, means for cutting off the advanced lead to length backwardly from the stripped end, and means for shifting the feeding means to advance the cut off lead longitudinally, means for bending a loop in the stripped end of the wire arranged to receive the stripped end as the cut off lead is advanced, and means operated by further movement of the lead advancing means for operating the bending means.

14. In a machine for preparing electrical conductor leads, means for holding and cutting a portion of the insulation at a free end portion of

an insulated lead wire, longitudinally movable feeding means for shifting the wire backward to strip the cut insulation from the wire, means for bending a loop in the stripped end of the wire, said feeding means arranged to shift the wire forward to insert the stripped end in the bending means, means operated by forward movement of the feeding means for operating the bending means, and a main driving means for operating the stripping means and the operating means for the bending means.

15. In a machine for preparing electrical conductor leads, means for stripping the insulation from a free end portion of an insulated wire including a forwardly movable member, means for bending a loop in the stripped end of the wire, means movable with said member for feeding the wire forwardly and inserting the stripped end in the bending means, and means operated by further forward movement of said member for operating the bending means.

16. In a machine for preparing electrical conductor leads, means for stripping the insulation from a free end portion of an insulated wire including a forwardly movable member, means for bending a loop in the stripped end of the wire comprising movable jaws to grip opposite sides of the wire, means movable with said member for feeding the wire forwardly and inserting the stripped end into said jaws, and means operated by further forward movement of said movable member to operate said jaws to bend the wire.

17. In a machine for preparing electrical conductor leads, means for stripping the insulation from a free end portion of an insulated wire including a movable member, a base member, a movable slide mounted on said member, means mounted on the slide and movable therewith for bending the stripped end portion of an insulated wire to form a loop, cooperating means on the slide and base operated by movement of the slide on the base for operating said bending means, and means operable by said movable member for shifting the slide to operate the bending means.

18. In a machine for preparing electrical conductor leads, a base member, a movable slide mounted on said member, means mounted on the slide and movable therewith for bending the

stripped end portion of an insulated wire to form a loop including opposed jaws at least one of which is movable, means for feeding the stripped end of a lead into a position between said jaws including a movable member, said base being provided with a cam slot, an operating means connected to the movable jaw and running in said slot, and means operable by the movable member for shifting the slide to operate the jaw through said operating means and slot.

19. In a machine for preparing electrical conductor leads, a base member, a movable slide mounted on said member, means on the slide for bending the stripped end portion of an insulated wire to form a loop comprising a pair of opposed jaws pivoted to the slide to move toward and from each other, means for feeding the stripped end of a lead into a position between the jaws including a movable member, said base being provided with cam slots, means in the slots and connected with the jaws for operating them by movement of the slide to bend a wire between them, and means operable by the movable member for shifting the slide to operate the jaws.
